UNITED STATES PATENT OFFICE.

JEAN ZVORIKIN, OF PARIS, FRANCE.

SPINNING AND TWISTING FRAME.

Application filed March 26, 1926, Serial No. 97,756, and in France February 3, 1926.

This invention relates to improvements in spinning, or twisting frames, being concerned with the mechanism for imparting twist to the thread in winding it on the bobbin, with the spindle and its actuating means, and with means for obviating inconveniences due to the breakage of the thread.

In continuous spinning and twisting frames heretofore usual there is provided a long rotating upright spindle which carries above the movable rail the bobbin on which the thread is wound and at its upper end the flyer which gives the yarn the desired twist. When the bobbin is full, it is necessary to dismount the flyer to withdraw the bobbin from the upper end of the spindle and replace it by an empty bobbin.

In accordance with the invention the flyer fixed to the rotating spindle is replaced by a device wholly independent of the rotating spindle, whence result advantages not only as regards facility of replacement of full bobbins by empty bobbins but also as regards the conduct of the spinning and twisting operations; particularly, the number of rotations of the spindle and the size of bobbin may be increased and generally there may be obtained an output considerably in excess of that obtainable with the usual spinning or twisting frame.

I am aware that it has previously been proposed to provide in such frames a flyer mounted independently of the spindle but in such case the spindle was fixed and served simply to support the bobbin.

In order that the invention may be better understood it is hereinafter described, but by way of example only, with reference to the accompanying drawings, in which:

Fig. 1 is an elevation of a spinning frame with the devices of the invention shown in section at the left hand side.

Fig. 2 is a part elevation part section of the mechanism for imparting twist to the thread.

Fig. 3 is a detail view of this mechanism displaced 90 degrees relatively to the axis of rotation.

Fig. 4 is a part elevation part section of

the bobbin-carrying spindle with bobbin in position.

Referring to the drawing, the twisting mechanism comprises a horizontal disc 1, (Figs. 1 and 2) fitted with two depending tubular arms 2 and 3 of which one only is operative, the other serving to balance or replace the first, if required. The disc 1 is mounted on a tube 4 supported for rotation in ball bearings 5 in the sleeve 6 mounted in the upper fixed rail 7. This disc receives its rotary movement from the roller 9 mounted on the shaft 10 (Fig. 1) transmitted by the cord 11 passing over the guide pulley 12 and around the pulley 13 screwed on to the tube 4 and thus constrained to rotate with the disc.

The yarn 14 after its passage between the drawing rollers 15 and through guide eyes 8 penetrates the tube 4 (Fig. 2), then traverses the eye 16 at the extremity of the arm 2, whether previously guided or not, depending on requirements and on the nature of the yarn, by the curls 17 and 18. It will be seen that each rotation effected by the disc 1 corresponds to one turn of twist of the thread.

The spindle 19 (Fig. 4) is free to turn around its axis in a support 20 locked by a nut 21 to a movable rail 22. This spindle 19 receives a rapid movement of rotation from the roller 9 transmitted by the cord 23 which passes over the guide pulley 24 fixed to rotate with the spindle. In consequence of its rapid rotation and of the resulting gyroscopic phenomenon, the axis of the spindle remains stationary without vibration.

The bobbin 25 rests freely on the spindle and presents a circular groove 26 engaged by springs 27 which prevent vertical shift of the bobbin during rotation. In fitting the bobbin in place, the springs pass by way of the notches 28 (Fig. 4) formed at diametrically opposed points in the circular shoulder 29 of the bobbin and enter the groove 26.

As shown in Fig. 1, the bobbin 25 is mounted on the same geometrical axis as the twist mechanism, and in its rising and falling movement communicated by the movable

2
rail 22 it passes between the two vertical arms 2 and 3. The thread leaving the eye 16 is thus wound on the bobbin 25 to which it communicates a movement of rotation braked in the usual manner to obtain a suitable speed relation of the disc 1 and bobbin 25. The movable rail 22 is lifted by the action of the chain 30 attached to the bracket 31 fixed to the rail, said chain being operated by the sector 32 to which is imparted by suitable means oscillating movement around an axis 33; the rail is permitted to descend under the action of its own weight. There are indicated at 22¹ and at 25¹ the upper positions of the rail 22 and of the bobbin 25.

10 To replace full bobbins by empty bobbins, the frame is stopped when the rail 22 is in lowered position; this replacement does not necessitate any dismounting of parts other than the bobbin, so that time is economized.

15 The invention presents over prior constructions other advantages which will be understood from the following.

20 In prior frame constructions the upper end of the long rotating spindle is overloaded by the somewhat heavy flyer, and is insufficiently balanced, it being necessary to unscrew it and rescrew it frequently to replace the bobbins; further, the spindle supports 25 the load of the full bobbin at the moment when the rail is in its upper position. In the arrangement of the invention there is obtained great stability of the several elements and notably of the axis of the spindle 30 which renders it possible to confine the thread to a predetermined path and largely to obviate risk of breakage. The speed of 35 rotation may also be increased so as to increase the output of the frame.

40 In known frames the thread leaving the guide follows a path which is distant from the geometrical axis of the spindle, being subject to the action of centrifugal force at the points where it is unsupported. Hence 45 results the phenomenon known as "ballooning". With the present arrangement, however, the lower guide 8 may be brought very close to the pulley 13 since the twist mechanism does not require to be dismounted. Further, the thread 14 follows the geometrical axis of spin up to the point where it leaves the disc 1, and in consequence the ballooning effect is considerably reduced—a circumstance which also permits increase of 50 the speed of rotation.

55 From the foregoing it will be seen that very high speeds may be used, which may amount in wet spinning to 9000 revolutions of the spindle per minute in frames in which the spindles are spaced apart 6½ centimetres with bobbins of a height of 9 centimetres. In the old style of frame with a maximum height of bobbin of 6 centimetres the speed was only 4000 revolutions per minute.

60 On account of the high speeds of rotation

it is necessary to provide an arrangement which will reduce to a minimum the inconveniences resulting from breakage of the thread, which inconveniences do not occasion excessive trouble in the old styles of frames because of the low speed. It is known that in case of breakage of the thread the yarn is wound on and entangled around the lower drawing roller which rotates continuously and that the operative is obliged to remove the yarn wound around the roller. To obviate necessity for this operation there is placed beneath the lower roller 15 a small diameter roller 34 of the same length, the arbor of which small diameter roller is mounted on one end of a bell-crank lever 35 fitted to rock on a fulcrum 36 and carrying at its opposite end a counterbalance weight 37 which presses the roller 34 against the drawing roller 15.

65 To replace full bobbins by empty bobbins, the frame is stopped when the rail 22 is in lowered position; this replacement does not necessitate any dismounting of parts other than the bobbin, so that time is economized.

70 The invention presents over prior constructions other advantages which will be understood from the following.

75 It is to be understood that the invention is not limited to the details of construction and arrangement described, but that the same may be varied without departure from the essence of the invention.

80 In particular there may be varied the means for rotating the disc 1 and the spindle 19; also, these elements may be mounted otherwise than as described, with or without ball bearings.

85 What I claim is:

1. A spinning couple comprising a rotary spindle, a thread-receiving bobbin mounted thereon and rotating independently thereof, and means for imparting a twist to the thread, said means including a rapidly rotating disk rotating on the same axis as the spindle and bobbin and having two depending arms on one of which the thread is guided to the bobbin.

105 2. A spinning couple comprising a rotary spindle, a thread-receiving bobbin mounted thereon and rotating independently thereof, means for imparting a twist to the thread, said means including a rapidly rotating disk rotating on the same axis as the spindle and bobbin and having two depending arms, and means for guiding the thread on one of the arms including spaced curls located along the arm and an eye at the lower extremity of such arm.

110 3. A spinning couple comprising a rotary spindle, a thread-receiving bobbin mounted thereon by being freely impaled on the spindle and rotating independently thereof, means for imparting a twist to the thread, said means including a rapidly rotating disk rotating on the same axis as the spindle and bobbin and having two depending arms on one of

- which the thread is guided to the bobbin, and means for moving the spindle and associated bobbin axially between the depending arms.
- 5 4. In a device of the class described, the combination of a spinning couple comprising a rotary spindle, a thread-receiving bobbin mounted thereon and rotating independently thereof, means for imparting a 10 twist to the thread including a rotary ro-
- tating disk having two depending arms, in combination with a scavenging roll located beneath the usual lower drawing roller for unwinding the yarn which has become wound on the drawing roller in case of 15 breakage of the thread.

In testimony whereof I have signed my name to this specification.

JEAN ZVORIKIN.
